CLAIM

The ornamental design for a combined hypodermic needle guide and guard, as shown and described.

DESCRIPTION

FIG. 1 is a perspective view of a combined hypodermic needle guide and guard showing my new design;
FIG. 2 is a top plan view thereof, the bottom view being a mirror image of the top view shown in FIG. 2;
FIG. 3 is a side elevational view thereof, the side opposite being a mirror image of the side shown in FIG. 3;
FIG. 4 is a front end elevational view thereof; and,
FIG. 5 is a rear end elevational view thereof.

FIG.1

FIG. 2

FIG. 3

FIG. 4

FIG. 5
